US0D1086635S

(12) **United States Design Patent** (10) **Patent No.:** **US D1,086,635 S**
(45) **Date of Patent:** **** Aug. 5, 2025**

(54) **PET TREAT**

(71) Applicant: **Spectrum Brands, Inc.**, Middleton, WI (US)

(72) Inventors: **Erin VanTrease**, Middleton, WI (US); **Allyse McCann**, Blacksburg, VA (US); **Tiffany Dawn Potter**, Pearisburg, VA (US)

(73) Assignee: **Spectrum Brands, Inc.**, Middleton, WI (US)

(**) Term: **15 Years**

(21) Appl. No.: **29/892,049**

(22) Filed: **May 12, 2023**

(51) LOC (15) Cl. **01-01**

(52) U.S. Cl.

USPC **D1/125**

(58) **Field of Classification Search**

CLAIM

The ornamental design for a pet treat as shown and described.

DESCRIPTION

The patent or application file contains at least one drawing executed in color. Copies of this patent or patent application publication with color drawing(s) will be provided by the Office upon request and payment of the necessary fee.

FIG. 1 is a perspective view of a pet treat according to the new design;

FIG. 2 is a left side view thereof;

FIG. 3 is a top plan view thereof; and,

FIG. 4 is a front view thereof.
